ARRANGEMENT FOR WALL ELEMENTS COMPRISING TWO SHEETS WITH INTERMEDIATE INSULATION

Bertil Jarreby, Molndal, Sweden, assignor to Aktiebolaget Svenska Fläktfabriken, Stockholm, Sweden
Filed Jan. 22, 1962, Ser. No. 167,822
Claims priority, application Sweden, Jan. 25, 1961,
737/61

2 Claims. (Cl. 52—303)

The present invention relates to a novel and improved arrangement in wall elements comprising two sheets with intermediate insulation and an enclosing frame.

Wall elements of the aforesaid type are at present applied to an increasing extent for the erection of walls in drying and conditioning plants, as covers for cylinder driers, etc. In such plants the air at the inner surface of the wall has in many cases a high relative humidity and due to the fact that for manufacturing reasons the sheets of the wall elements cannot be secured to the frame in such a manner that a complete air sealing is obtained, there is always the risk of moist air entering the space between the sheets. When this air is cooled its condensed moisture will be absorbed by the intermediate insulation and deposited both on the inner surface of the external sheet and on the frame. As there is only very limited natural air exchange with the ambient air through leaks in the external sheet, the said moisture deposit remains within the intermediate space where it not only constitutes corrosion risk but also contributes to a deterioration of the heat insulating capacity of the insulation and in certain cases even effects complete destruction of the insulation.

It is the object of the invention to eliminate the aforesaid drawback in a simple as well as reliable manner. The invention is characterized in that the insulation is subdivided into a plurality of vertical fields with free spaces therebetween which, through openings provided in the upper and lower frame portions of the wall element, communicate with the ambient air for utilizing the said free spaces for ventilating the interior of the wall element.

A preferred embodiment of the invention is characterized in that the wall element comprises one entirely plane and one slightly corrugated sheet, the said plane sheet being riveted to the frame by employing an intermediate sealing strip while the corrugated wall sheet is riveted to the frame without such sealing strip whereby the wave troughs of the corrugated sheet form the said ventilation openings to the said free spaces in the interior of the wall element.

More specifically, the aforesaid ventilation is rendered possible in that the wall sheets are made of thin material glued on the intermediate insulation, in such a manner that they together form a slab of a thickness somewhat smaller than the width of a groove provided in the frame and enclosing the slab, and in that the said slab is secured to the frame by so-called pope or blind riveting of the two wall sheets, the wall sheet last riveted along the frame thereby forming a slightly waved or corrugated contact surface with the wave troughs constituting the said ventilation openings. The so-called "pope" rivets are of the type which can be inserted in a hole and by external pressure on a sleeve and pull on a stem have a head formed

2

on the inner end of the sleeve. Similar fasteners in common use are known as "cherry" rivets and "mollys."

The bottom portion of the frame is provided with a plurality of through holes through which any condensate collected therein may be drained off.

The invention will now be described more in detail with reference to the accompanying drawings showing by way of example an embodiment of a wall element according to the invention, and wherein

10 FIG. 1 shows a wall element in elevation, wherein the frame and sheets are partially cut off to show the type of intermediate insulation,

FIG. 2 is a section through the upper portion of the frame along the line 2—2 in FIG. 1,

15 FIG. 3 is a section of the bottom portion of the frame along the line 3—3 in FIG. 1, and

FIG. 4 is a transverse section along the line 4—4 in FIG. 1.

20 In the drawing, 1 designates a frame for a wall element according to the invention. Between an inner sheet 2 and an outer sheet 3 secured to the frame is laid insulation material 4 which in the embodiment shown is Wellit. According to the invention the insulation is subdivided into a plurality of vertical fields with free spaces 9 therebetween which form vertical through channels for ventilation. The wall sheets are secured to the frame by means of rivets 6 in such a manner that for obtaining greatest possible sealing effect towards the inside a sealing strip 7 is provided between the inner sheet 2 and the frame

30 1. For securing the external sheet which is slightly corrugated no sealing is employed with the result that spaces are formed at the wave troughs, which spaces serve as ventilation openings 5 connecting the ambient air with the said free spaces.

35 The said ventilation openings may be obtained without using an external sheet which is corrugated in advance, in that the wall element is constructed of thin wall sheets glued to the insulation material, thus forming a slab of a thickness somewhat smaller than the width of a groove

40 provided on the frame and enclosing the slab, the said slab being secured to the frame by so-called pope or blind riveting. In this embodiment the inner sheet, when being riveted, forms a slightly corrugated contact surface with the wave troughs constituting the said ventilating openings.

45 The bottom portion of the frame is provided with a plurality of through holes 8 for draining off any condensate flowing down in the space between the wall sheets, and collecting in the groove in the bottom of the frame.

50 2. The design of the frame as well as the fastening of the wall sheets may be modified, of course, in different ways within the scope of the inventive idea.

What I claim is:

55 1. In wall elements comprising two sheets with intermediate insulation and a surrounding frame having a groove therein receiving said sheets and insulation, the insulation being subdivided into a plurality of vertical fields with free spaces therebetween, openings at the upper and lower ends of the wall element communicating with the ambient air in order to utilize the said free spaces for ventilating the interior of the wall elements, the improvement wherein the wall sheets consist of thin material glued to the insulation therebetween, said sheets and insulation together forming a slab of a thickness some-

what less than the width of the groove in the frame, the wall sheets being secured to the frame by blind rivets, the wall sheet last riveted along the frame thereby forming a slightly waved contact surface with the wave troughs constituting the said ventilation openings.

2. An arrangement according to claim 1 wherein the groove in the bottom portion of the frame is provided with a plurality of through-holes for draining off any condensate collected therein.
